UNITED STATES PATENT OFFICE.

CHARLES J. VENN, OF CHICAGO, ILLINOIS, ASSIGNOR TO CENTURY RUBBER WORKS,
OF CICERO, ILLINOIS, A CORPORATION OF ILLINOIS.

DESIGN FOR A TIRE TREAD.

Application filed May 13, 1922. Serial No. 2,212. Term of patent 14 years.

To all whom it may concern:

Be it known that I, CHARLES J. VENN, a citizen of the United States, residing at Chicago, Cook County, Illinois, have invented a new, original, and ornamental Design for a Tire Tread, of which the following is a specification, reference being had to the accompanying drawing, forming part thereof, in which—

Fig. 1 is a face view of the tire tread, and Fig. 2 is a section on the line 2—2 of Fig. 1.

I claim:

The ornamental design for a tire tread, substantially as shown.

CHARLES J. VENN.
